UNITED STATES PATENT OFFICE.

PETER DUFF HEAN AND JOHN J. EGAN, OF MEDIA, PENNSYLVANIA.

TROLLEY-HEAD.

SPECIFICATION forming part of Letters Patent No. 758,445, dated April 26, 1904.

Application filed December 26, 1903. Serial No. 186,657. (No model.)

To all whom it may concern:

Be it known that we, PETER DUFF HEAN, a subject of the King of Great Britain, and JOHN J. EGAN, a citizen of the United States, residing at Media, in the county of Delaware and State of Pennsylvania, have invented certain new and useful Improvements in Trolley-Heads; and we do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in trolleys for overhead electric railways; and the object of the invention is to produce means whereby the sheave or trolley-wheel may be prevented from jumping from the trolley-line and in the provision of mechanism for automatically throwing guard-arms to relieve the trolley-wheel from the line-wire in case an obstruction is met with upon the wire.

More specifically, our invention comprises the provision of guard members which are carried by the casting which holds the trolley-wheel and designed to normally maintain the trolley-wheel in engagement with the line-wire and in the provision of spring-actuated apparatus whereby the guard-arms may be thrown into such positions as to allow the wheel to be withdrawn from the line-wire; also, in the provision of a trip-lever so arranged that any obstruction upon the line-wire will actuate the trip to throw the guard members into position to allow the trolley-wheel to be thrown from the line-wire before the obstruction comes in contact with the trolley wheel or pole.

Our invention consists, further, in various features and details of construction, together with combinations of parts, which will be hereinafter fully described and then specifically defined in the appended claims.

The invention is illustrated in the accompanying drawings, which, with the letters of reference marked thereon, form a part of this application, and in which drawings similar let-

ters of reference indicate like parts in the views, in which—

Figure 1 is a side elevation, partly in section. Fig. 2 is an end elevation showing the relative positions of the guard members and trolley-wheel or sheave. Fig. 3 is a sectional view on line 3 3 of Fig. 1. Fig. 4 is a detail view, in side elevation, of the rack and spring-carrying box. Fig. 5 is an end view of the rack and box shown in elevation in Fig. 4. Fig. 6 is a top plan view of a modified form of guard-operating mechanism. Fig. 7 is a sectional view of the modified form.

Reference now being had to the details of the drawings by letter, A designates a trolley-pole carrying a trolley-head A' made of any suitable material, and carrying a pin B, upon which a trolley-wheel or sheave C is journaled in the usual manner. Integral with or secured to the trolley-head are the tubings D, which rise from the plate α , which is integral with or secured to the trolley-head, in which the shank portions E' of the guard members E are journaled, said shank portions of the guard members passing through apertures in said plate, which register with the bores of the tubular members. Each of said guard members has a shoulder E² adapted to rest upon the upper ends of the tubular portion D to support said members. The upper end of each guard member is curved in hook form, as shown clearly in Fig. 2 of the drawings, and when said curved ends are turned toward each other a slight space intervenes between the same and they are then positioned so as to engage the trolley-line in case the trolley-head has a tendency to jump from the line-wire. Mounted upon the shank portions of the guard members which project below the plate α are segment-gears F, which are adapted in their operative movements to have a one-quarter rotary movement. Pins or keys e are inserted through the registering apertures in the shank portions of said guard members and segment-gears and serve as a means to cause the guard members and segment-gears to rotate together and also to lock the guard members within their bearings.

A sliding rack H is provided having teeth upon its opposite faces, which are adapted to

mesh with the teeth of the segment-gears F, as shown clearly in the detail view of the drawings. Said rack has slots H' upon the opposite faces of the shank portion thereof 5 immediately above the teeth upon its faces, provided to receive the edges of an elongated slot formed in the plate a and upon which the rack is guided in its reciprocal movements. The upper portion of the rack member is 10 formed into a casing F², which is adapted to form a housing for a spring K, which is provided for the purpose of returning the segment-gears and the rack to their normal positions and also to throw the guard members 15 into their positions to retain the trolley-head to the line-wire. A bolt K' has one end fixed in a bracket extension a' rising from said plate a, and said bolt extends into the housing or casing F², and the head k of said bolt 20 serves as an abutting means for one end of the spring, while the other end of the spring bears against the inner end of said housing or boxing F².

Mounted in the ears N, which are integral 25 with the trolley-head, is a pin M, upon which a lever O is fulcrumed, one end of said lever being pivotally connected at h to the inner end of said rack-bar, while the other end of the lever O is connected at O' to a rope Q, 30 which passes over the sheave Q' and is adapted to be positioned within convenient reach of an operator, whereby when it is desired to throw the guard members into positions to allow the trolley wheel and head to be relieved from the line-wire the rope may be 35 pulled upon, which will cause the rack-bar to be thrown away from the trolley-wheel and the segment-gears and the guard members, which move with them, into positions in which 40 the hooked ends thereof will be disposed in parallel planes, thus allowing the trolley-head to be withdrawn from the line-wire without any interference. In order to increase the tension upon the lever O for the purpose of 45 withdrawing the rack to its normal position, an auxiliary spring P is provided, one end of which is secured to the upper portion of the lever O, while its other end is fastened to an eye P', carried by the trolley-pole. 50 In order to provide means for automatically throwing the guard members into a position to allow the trolley-head to be withdrawn from the line-wire in case of the breakage of an ear-plate bolt or when any obstruction is 55 met with which would cause damage by coming forcibly against the pole or sheave, which would have a tendency to break parts of the apparatus if the guards were in position to engage the line-wire, we provide a trip-lever 60 R, which is pivoted to the trolley head or pole at R', the lower end of which lever R is pivotally connected at R² to one end of the link R³, which in turn is pivotally connected at R⁴ to the lever O. The free end of the lever R 65 normally rests in the position shown in full

lines at r, in which position it is disposed immediately in front of the trolley wheel or shaft and is adapted to receive the impact of any foreign object against which the lever may come in contact for the purpose of tripping the lever into the position shown in dotted lines, in which position the rack-bar will be actuated longitudinally and the segment-gears rotated and the guards thrown into releasing positions to allow the trolley and sheave carried thereby to quickly be thrown away from the line-wire in case of an emergency. 70 75

In Figs. 6 and 7 of the drawings we have shown a slight modification of the apparatus for actuating the guard members, in which drawings the guard members are pivotally mounted in the trolley-head, being held therein by means of keys e', and instead of the spring K and housing therefor we provide a reciprocating slide-block T, which is mounted in a dovetailed groove in the trolley-box; said sliding block T being pivotally connected to the link T', which in turn is pivotally connected to one end of the lever T², which is 80 mounted on a pivot-pin in a slot or recess in the trolley-head. A spring T³ is secured at one end of the lever T² and has its other end fastened to the trolley-pole, and the object of the spring is to normally hold the guard members with their curved hooked ends adjacent to each other, or in positions to engage and hold the trolley-head to the line-wire. For throwing the guard members for releasing the trolley-head from the line-wire we provide 85 the slotted arms S, which are keyed to the shank portion of the guard members and have elongated slots S', in which a pin W, carried by the slide-block T, has a play, the two arms being given a partial rotary movement as the 90 slide-block T is reciprocated, as will be readily seen. 95 100

The operation of our apparatus will be readily understood and is as follows: When the trolley-head is desired to be adjusted for being held to the line-wire, the parts assume the position shown in solid lines in the drawings, in which the trolley-head is held to the line-wire and prevented from jumping away from the wire, which is a common fault with 110 trolleys in which no provision is had for avoiding this trouble. When it is desired for any purpose to allow the trolley-head to be withdrawn, the operator by pulling upon the rope Q may, through the lever rack-and-pinion mechanism, cause the guard members to be thrown so that a free passage will be afforded between the hooked ends of the guard members, through which the line-wire may readily pass without interference. In case of any 115 obstruction being upon the wire the trip-lever is normally in a position so that it will receive the impact against the obstruction before the matter strikes the trolley-pole or sheave, and as the free end of the lever R 120 125 130

- comes in contact with the obstruction it will be thrown into the position illustrated in dotted lines, through which rack and segment connections the guard members will be quickly 5 thrown open to allow the trolley-head to be withdrawn from the line-wire without the breakage of parts of the apparatus, which would be the case were it not for the provision of the means described.
- 10 While we have shown a particular form of apparatus for operating the guard members and also the tripping mechanism for automatically throwing the guards open, it will be understood that we may make alterations, if desired, in the various details of construction of these parts mentioned, as well as in other features of the apparatus, without in any way departing from the spirit of the invention.
- Having thus described our invention, what 20 we claim as new, and desire to secure by Letters Patent, is—
1. A trolley apparatus comprising in combination with a trolley-head, guard members journaled in suitable bearings upon the trolley-head and provided with hooked ends, segment-gears fixed to said members, a rack-bar having teeth in mesh with said gears, a spring-actuated lever mechanism connected to said rack, whereby as the rack is moved in one direction, the guards are opened, and the reverse direction, closed, as set forth.
  2. A trolley mechanism comprising a trolley-head, guard members journaled in suitable bearings upon said head, tripping mechanism 35 and means intermediate the same and said guard members to automatically open the guard members, and means for closing the same, as set forth.
  3. A trolley apparatus comprising in combination with a trolley-head, guard members journaled in suitable bearings upon the trolley-head and having hooked ends normally held in positions to hold the trolley-head from jumping from the line-wire, a pivotal trip-lever 40 with its free end positioned in advance of the trolley-head, and connections between said lever and the guard members for automatically opening the same to allow the trolley to be withdrawn from the line-wire, and means 45 for closing the guard members, as set forth.
  4. In combination with a trolley-head, guard members journaled in suitable bearings upon said head and having hooked ends adapted to normally hold the trolley-head from jumping 55 from the line-wire, a pivotally-mounted trip-lever with its free end in advance of the trolley-head, reciprocating mechanism for opening and closing said guard member, and lever and link connections between said mechanism 60 and the trip-lever, as set forth.
  5. A trolley apparatus comprising in combination with a trolley-head, guard members journaled in suitable bearings upon said head

and having hooked ends normally held to prevent the trolley from jumping from the line-wire, segment-gears keyed to the shank portions of said guard members, a reciprocal rack having teeth upon its opposite faces which are in mesh with the segment-gears, a lever pivotally mounted upon the trolley-head and having pivotal connection with said rack, and spring mechanism for holding the guard members closed, as set forth.

6. A trolley apparatus comprising in combination with a trolley-head, guard members journaled in suitable bearings thereon, and having hooked ends, segment-gears keyed to the shank portions of said members, a reciprocal rack-bar having teeth upon its opposite faces in mesh with said gears, a housing carried by said rack-bar, a spring mounted in said housing, a bolt fixed at one end to the trolley-head and passing into said housing, and having a head against which one end of the spring bears, a pivotal lever mounted upon the trolley-head and having pivotal connection with said rack, and rope connection with said lever, as set forth.

7. A trolley apparatus comprising in combination with a trolley-head, a pole supporting the same, a sheave mounted in said head, guard members journaled in the trolley-head having hooked ends adapted to hold said sheave from jumping from the trolley-line wire, segment-gears keyed to the shank portions of the 95 guard members, a reciprocable rack having teeth upon its opposite faces in mesh with the teeth of said segment-gears, a pin mounted in the opposite walls of the trolley-head, a lever pivotally mounted upon said pin having pivotal connection at one end with said rack, a spring mechanism for normally holding the guard members closed, a pulley mounted upon the trolley-pole, and a rope passing about said pulley and connected to the end of said pivotal 100 lever, as set forth.

8. In combination with a trolley head and pole supporting the same, a sheave journaled in said head, guard members journaled in the head having hooked ends, segment - gears 110 keyed to the shank portions of said guards, a reciprocal rack having longitudinal grooves in its opposite faces adapted to receive the marginal edges of the slot of a plate forming a portion of the trolley-head, and lever mechanism connected to said rack-bar for actuating the same, as set forth.

In testimony whereof we hereunto affix our signatures in presence of witnesses.
